[57] **CLAIM**

The ornamental design for a core for an elongate strip, as shown.

DESCRIPTION

FIG. 1 is a side perspective view of a core for an elongated strip showing my new design;

FIG. 2 is a side elevational view thereof;

FIG. 3 is an opposite side elevational view thereof;

FIG. 4 is an edge elevational view thereof;

FIG. 5 is a top plan view thereof;

FIG. 6 is a cross-sectional side view thereof as taken from line 6—6 of FIG. 2.

FIG. 1.FIG. 4.FIG. 2.FIG. 5.FIG. 6.FIG. 3.
